UNITED STATES PATENT OFFICE.

CHARLES REMER, OF RACINE, WISCONSIN.

FOOTWEAR.

1,089,791.

Specification of Letters Patent. Patented Mar. 10, 1914.

Application filed March 14, 1911. Serial No. 614,300.

To all whom it may concern:

Be it known that I, CHARLES REMER, a citizen of the United States, residing at Racine, in the county of Racine and State of Wisconsin, have invented new and useful Improvements in Footwear, of which the following is a specification.

This invention relates to improvements in boots, shoes and other footwear and has particular reference to a protector for boots, shoes, etc., which in use are subjected to unusual or very rough wear.

The invention comprises a protector plate which provides the sole and heel portion, and a continuous upstanding flange through which passes the rivets or other means for securing the protector to the shoe.

With the above, and other objects in view, which will appear as the nature of the description progresses, the invention resides in the novel construction and arrangement of parts hereinafter fully described and claimed.

In the drawings Figure 1 is a perspective view of a shoe showing the protector connected therewith. Fig. 2 is a transverse sectional view upon the line 2—2 of Fig. 1. Fig. 3 is a longitudinal sectional view upon the line 3—3 of Fig. 2. Fig. 4 is a perspective view of the protector alone and looking toward the bottom thereof.

Referring to the drawings, the boot or shoe protector is clearly shown in Fig. 4 of said drawings, comprising a sole portion 1, heel 2, and shank 3. The heel 2 is centrally reduced to provide a pocket 4, the said pocket being adapted to receive a suitable cushion member which is designated by the numeral 5. It will be noted by reference to Fig. 3 of the drawings that the pocket is designed to occupy the full space provided for the heel, and that the sides or outer edges of the said heel are arranged at an angle as designated by the numeral 6. The protector is preferably constructed of aluminum or other light metal and the said protector is provided with an upstanding marginal guard or flange 7. The flange 7

is provided with a plurality of perforations 8, and the said perforations are adapted to receive suitable rivets 9, the latter preferably having their ends bifurcated and adapted to be inserted through the shoe vamp which is designated by the numeral 10. When the said rivets are in position, their bifurcated ends are bent in opposite direction so that the shoe is securely connected with the protector.

By reference to Figs. 2 and 3 of the drawings, it will be noted that the vamp of the shoe has its lower edges bent inwardly upon the bottom of the protector and the said in-turned portions are provided with a plurality of upwardly extending nails 11, the latter being adapted to engage with the insole 12 of the said shoe. The insole 12 is formed of some coarse material and the foot of the wearer is protected through the medium of a second insole 13 which is constructed of some soft material such as hair or the like.

The under face of the protector is serrated upon what may be termed the sole and the heel of said protector, as clearly shown in Fig. 4 of the drawings, and designated by the numerals 14 and 15 respectively. The toe portion of the protector is provided with a plurality of downwardly extending lugs 16, the said lugs and the serrations adapted to serve as means for preventing accidental slipping of the user of the device. It will be noted that the bottom or sole portion 1 is rounded so that the said sole serves as a rocker which provides for the free movement or elasticity of the device when positioned upon the foot of the wearer, thus not only adding to the comfort of the wearer but also affording what may be termed propelling means which greatly assists the wearer in walking.

Having thus fully described the said invention what I claim is:—

In a device of the class described including a metallic protector for shoes provided with an upstanding continuous marginal guard or flange having a series of perforations, means passing through said perfora-

tions and through the vamp of the shoe for securing the guard thereto, the upper of the shoe having its lower extremity bent inwardly and provided with a plurality of 5 nails, an insole adapted to be engaged by the nails of the inturned portion of the shoe and extending over and in engagement with the cushioning member, and a second insole

constructed of some soft material adapted to overlie the first named insole.

In testimony whereof I affix my signature in presence of two witnesses.

CHARLES REMER.

Witnesses:

BYRON F. BLISH,

ELIZABETH B. OWEN.
